UNITED STATES PATENT OFFICE.

WILLIAM HATTON STEVENS, OF ALTOONA, PENNSYLVANIA.

DUST-COLLECTOR.

1,232,865.

Specification of Letters Patent. Patented July 10, 1917.

Application filed March 14, 1916. Serial No. 84,011.

To all whom it may concern:

Be it known that I, WILLIAM HATTON STEVENS, a citizen of the United States, residing at Altoona, in the county of Blair and State of Pennsylvania, have invented certain Improvements in Dust-Collectors, of which the following is a specification.

My invention relates to improved means for collecting dust, carried in suspension by air or other gas, and, in its preferred form, it comprises a conduit containing an expansion and collecting chamber provided with baffles, ducts for delivering steam within the chamber, and ducts for delivering water within the chamber.

In the operation of my invention, the air or gas laden with dust is blown or drawn through said chamber, where it is expanded, baffled, and mixed with steam, to effect deposition of the dust, and the water is delivered within the chamber in the form of fine streams or sprays, to condense the steam, wash down the deposited solid matter and wash the air, which is thus purified when it escapes from the chamber.

In the accompanying drawings, Figure 1 is a diagrammatic elevational view of a dust collecting system embodying my improvements; Fig. 2 is an enlarged part sectional plan view of the collecting chamber with its connections; and Fig. 3 is an enlarged part sectional elevation of collecting chambers with connections therefor.

The invention, in the form in which it is embodied in the accompanying drawings, comprises one or more chambered cylinders or shells 1, formed of sheet metal, each being provided with a closed top 1^a and with a conical bottom or hopper 1^b having a discharge duct 2. Each shell is supported by brackets 3 fixed to the lower part thereof and resting on piers 4.

Baffles 5 are fixed within each shell and inclined downwardly from opposite parts thereof, alternating so that a zig-zag course is provided for the dust laden air or gas, which is baffled thereby. The baffles are thus disposed so that water falling thereon will run down from one to another in a zig-zag course, washing down deposits and crossing the course through which the gas must travel.

A steam pipe 6 is provided with a section 6^a which extends around or partially around an intermediate zone of each shell 1 and with sections 6^b which extend from the section 6^a

through the shell and downwardly therein, the sections 6^b being perforated and spaced within the shell so that steam jets can be delivered therefrom and distributed thereby under control of a valve 7 in the section 6^a.

A water pipe 8 is provided with sections 8^a which extends to the upper zones of the respective shells 1, with the laterally extending sections 8^b which are connected with the sections 8^a through the shell, with the sections 8^c branching laterally from the sections 8^b, with the sections 8^d which extend downwardly from the ends of the sections 8^c, and, with the sections 8^e which extend laterally from the bottoms of the sections 8^d beneath the baffles 5. The sections 8^b, 8^c, 8^d, and 8^e are perforated and disposed within the shell so that water under control of a valve 9 in the section 8^a can be sprayed and distributed in the course of the air or gas and solid matter deposited can be washed down through the shell.

An inlet duct 10 delivers the air or other gas containing dust or other solid matter to be collected through the lower part of each shell 1 to a part of its chamber below the lowermost baffle 5; such gas or air being baffled, expanded, mixed with steam and washed within the chamber through the functions of the parts 5, 6^b, and 8^b to 8^e.

The purified air or gas escapes from each shell through a duct 11 connected with the top thereof and extending downward to an exhaust manifold or box 12 having a hopper bottom 12^a into which the pipes 2 discharge in the form illustrated. The box or passage 12 is provided with the side openings 12^b guarded by the upwardly inclined deflectors or baffles 12^c, the air or gas escaping upwardly through the openings. Any solid matter deposited within the box is washed down by rain caught by the deflector 12^c, and, in case of need, water can be delivered upon the deflectors to wash down solid matter, which is discharged through the bottom 12^a and the discharge duct 16 connected therewith.

The air or gas containing solid matter to be collected is, in the diagrammatic view shown in Fig. 1, drawn by a fan 13 from any place containing or thing delivering solid matter in suspension, as a grain cleaner, oat clipper, hard wood working milling machine, or the like; the fan delivering such air or gas laden with solid matter through the duct 14 to a usual collecting vessel 15,

which delivers the gas with the remaining suspended solid matter to the duct 10.

It will be observed that the dust laden air passes through the fan 13, which forces it through the passage comprising the parts 5 14, 15, 10, 11, and 12, which increases progressively from the fan, the inlet to the duct 10 being smaller than the outlet therefrom, the duct 11 being larger than the outlet from the duct 10 and smaller than the outlets 10 from the box 12, and the sum of the outlets 12^b of this box being greater than the combined cross sections of the ducts 11, whereby back pressure is prevented, the 15 power required to drive the fan is reduced, better deposition of the dust in the chamber 1 is secured, and clogging of the fan by moisture, as would take place if it were used as a suction rather than as a pressure device, 20 is avoided.

Having described my invention, I claim:

1. In mechanism of the character described, a baffled passage, in combination with a box into the top of which said passage discharges, said box having a lateral aperture, a deflector adjacent to said aperture, and a bottom outlet.

2. In mechanism of the character de-

scribed, a plurality of baffled chambers, in combination with an exhaust chamber, ducts 30 whereby the tops of said baffled chambers are connected with the top of said exhaust chamber, and bottom ducts by which the respective chambers are adapted to discharge their solid and liquid contents.

3. In mechanism of the character described, a conduit comprising a chamber adapted for depositing and collecting dust contained in air passed therethrough, and an exhaust chamber having lateral apertures, deflectors adjacent to the respective apertures and a bottom outlet, for separating and discharging dust and air delivered from said chamber first named.

4. In mechanism of the character de- 45 scribed, a blower, an exhaust chamber, and a conduit through which said blower forces air to said chamber, said conduit comprising in sequence from said blower to said exhaust chamber a collecting vessel and a 50 baffled passage having means for delivering steam thereto.

In testimony whereof I have hereunto set my name this 10th day of March, 1916.

WILLIAM HATTON STEVENS.
